SQUEEZE BOTTLE

Banjamin Weiner, Stamford, Conn., assignor to Grow Chemical Corporation, New York, N.Y., a corporation of New York

Filed Aug. 19, 1969, Ser. No. 18,758

Term of patent 14 years

Int. Cl. D9—01

U.S. Cl. D9—2

FIG. 1

FIG. 2

FIG. 3

FIG. 4

FIG. 1 is a perspective view of a squeeze bottle showing my new design;

FIG. 2 is a front elevational view;

FIG. 3 is a side elevational view, the opposite side being a mirror image of the side shown; and

FIG. 4 is a rear elevational view thereof.

I claim:

The ornamental design for a squeeze bottle, as shown and described.
